* cited by examiner

Primary Examiner—Cathron C Brooks*Assistant Examiner*—Deanna Fluegeman(74) Attorney, Agent, or Firm—Banner & Witcoff, Ltd.(57) CLAIM

The ornamental design for a display screen with icon or packaging with surface ornamentation, as shown and described.

DESCRIPTION

The FIGURE is a front view of a display screen with icon or packaging with surface ornamentation showing my new design.

The broken line showing of the display screen or packaging forms no part of the claimed design. The portion of the display screen with icon or packaging with surface ornamentation that is shown forms part of the claimed design.
